Application February 28, 1950, Serial No. 8,217

Term of patent 14 years

(Cl. D8—2)

To all whom it may concern:

Be it known that we, Louis K. Richardson and Thomas E. Pope, are respectively citizens of the United States, residing at Seattle, Washington and Kodiak, Alaska have invented a new, original and ornamental Design for an Edible Container, of which the following is a specification, reference being had to the accompanying drawings, forming part thereof:

Fig. 1 is a front perspective view of an edible container, showing our new design;

Fig. 2 is a side elevational view; and

Fig. 3 is a top plan view thereof.

The back and side of the container are substantially similar in appearance to the front and side disclosed on the drawing.

We claim:

The ornamental design for an edible container, as shown and described.

LOUIS K. RICHARDSON.
